UNITED STATES PATENT OFFICE.

EMORY I. NICHOLS, OF SAN FRANCISCO, CALIFORNIA.

VICE.

SPECIFICATION forming part of Letters Patent No. 380,401, dated April 3, 1888.

Application filed December 14, 1887. Serial No. 257,903. (No model.)

To all whom it may concern:

Be it known that I, EMORY I. NICHOLS, a citizen of the United States, and a resident of the city and county of San Francisco and State 5 of California, have invented certain new and useful Improvements in Vise-Equalizers, of which the following is a specification.

My invention relates to improvements in that class of vise-equalizers in which a toothed sector or gear-wheel works in a rack guided by suitable guides held in position by springs, and the center of toothed sector or gear-wheel connected to the movable jaw of vise by bars or a triangle.

15 My improvements are embodied in the mechanism illustrated in the accompanying drawings, in which—

Figure 1 is a side elevation showing the construction of my improvements in conjunction 20 with the bench-jaw and screw. Fig. 2 is a view of sector-springs and end section of rack.

The same letters refer to the same or corresponding parts throughout the two views.

A is a toothed sector working in the rack B, 25 and is held to its engagement with the rack by the tension-springs C C'. The ends of springs are secured to the sides of sector A and rack B by the studs D and D'. The lower end of sector A at h is slotted for the reception of 30 bars or triangle E E'. One end of each bar is pivotally connected to sector at h. The other ends of bars pass through a slot in the stationary jaw H, and are secured to the movable jaw I, one end at d, or near the screw, and 35 the other end at d', or near the bottom of movable jaw. The rack B is made with sides or guides, and is secured to the under side of bench-top or to a cross-bar, k. It will thus be seen that by the movement of the screw F, Fig. 40 1, the center or lower end of sector at h will be moved in a horizontal line, which is attained

by the sector rolling on its rim, thereby keeping the center h always the same distance from the bar k. Then the bar E, being connected to the center of sector at h and the movable jaw 45 at d, or near the screw F, the center h will move the same distance as the movable jaw at d. Then the bar E', being connected to the center of sector at h and the lower end of the movable jaw at d', the movable jaw at d' will 50 move the same as at d, thereby keeping the movable jaw always parallel with the stationary jaw H.

I do not confine my improvements to one sector. There may be one or more sectors or 55 full circles of a greater or less radius, with or without the rack B.

Having thus described my invention, what I claim as new, and desire to secure by Letters Patent, is—

1. In a vise, the toothed sector A, slotted at h for the reception of bars E E', having the studs D' D' to engage the springs C C', the rack B, with sides and studs D D to engage springs C C' and secured to cross-bar k, the 65 springs C C', by which the sector A is held to its engagement with rack B, and the bars or triangle E E', pivotally connected to sector A, and secured to movable jaw of vise, substantially as and for the purpose described. 70

2. The combination, with the movable jaw I of a vise, of the stationary jaw H, the screw F, the toothed sector A, the rack B, the springs C C', and the bars or triangle E E', substantially as and for the purpose described. 75

In witness whereof I have hereunto set my hand.

EMORY I. NICHOLS.

Witnesses:

GEO. L. FITCH,
SAMUEL HOCKING.
